R. G. BABB

BIAS FURNITURE

Filed May 15, 1923

UNITED STATES PATENT OFFICE.

ROBERT G. BABB, OF PORT ARTHUR, TEXAS.

BIAS FURNITURE.

Application filed May 15, 1923. Serial No. 639,127.

To all whom it may concern:

Be it known that I, ROBERT G. BABB, a citizen of the United States, residing at Port Arthur, in the county of Jefferson and State of Texas, have invented new and useful Bias Furniture, of which the following is a specification.

By way of explanation it may be stated that, for reasons well understood by those skilled in the printer's art, the lines of a form often must not be disposed at right angles to the line of advance of the inking roller. In order to secure the desired result, it has been proposed hitherto to provide what is known as a bias chase, that is a chase provided with an opening, the edges of which are not disposed parallel to the outer edges of the chase. This expedient, however, renders it necessary for a printer to go to the expense of purchasing a bias chase, and the present invention aims to provide a simple means whereby an ordinary chase may be made to produce the same results as a bias chase without in any wise impairing the utility of the ordinary chase as such.

It is within the province of the disclosure to improve generally and to enhance the utility of devices of that type to which the invention appertains.

With the above and other objects in view, which will appear as the description proceeds the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in plan, an ordinary chase equipped with the furniture forming the subject matter of this application, the form being locked in place; Figure 2 is a section taken approximately on the line 2-2 of Figure 1, the form being omitted.

In the drawings, the numeral 1 marks a chase of rectangular outline, having a rectangular opening 2, the edges of which are disposed parallel to the outer edges of the 50 chase, wedge-shaped pieces 3 of furniture cooperating with the chase along the edges of the opening, and forming a second rectangular opening 4 the edges of which are disposed out of parallelism with the outer 55 edges of the chase, the device being further characterized by the fact that the reduced end 5 of each piece 3 of furniture extends across the wide end 6 of an adjoining piece of furniture. It is obvious that when the 60 form 7 is locked in the opening 4, all of the advantages of a bias chase will be secured, it being unnecessary for the printer to buy a bias chase, and the ordinary chase being capable of use in the regular way, when the 65 furniture 3 has been removed.

What is claimed is:

1. In a device of the class described, a chase of rectangular external outline and symmetrical with respect to its longitudinal 70 axis, the chase having a rectangular opening the edges of which are parallel to the outer edges of the chase, and wedge-shaped pieces of furniture cooperating with the chase along all of the edges of the opening, the 75 pieces of furniture forming a second rectangular opening the edges of which are disposed at an acute angle to the adjacent inner and outer edges of the chase.

2. A device of the class described, constructed as set forth in claim 1, and further characterized by the fact that the reduced end of each wedge-shaped piece of furniture extends across the wider end of an adjoining piece of furniture. 80

In testimony that I claim the foregoing as my own, I have hereto affixed my signature in the presence of two witnesses.

ROBERT G. BABB.
